UNITED STATES PATENT OFFICE.

GASTON VENDITTI, OF PARIS, FRANCE.

THREAD-TACKING MACHINE.

Application filed August 9, 1922. Serial No. 580,768.

To all whom it may concern:

Be it known that I, GASTON VENDITTI, a subject of the King of Italy, and residing at Paris, France, have invented certain new and useful Improvements in Thread-Tacking Machines, of which the following is a specification.

The present invention relates to a portable machine, which is moved by hand over two thicknesses of cloth or the like so as to follow a predetermined outline, and which is intended to form tacking threads through the two thicknesses of cloth, thereby producing loops upon the under face of the lower cloth, so that by slightly separating the two thicknesses of cloth and by cutting the thread between them the thread-ends or the loops remaining upon the two opposite faces, form on the two thicknesses of cloth, two symmetrical outlines or patterns. This machine thus enables two symmetrical pieces of cloth to be obtained, for instance for sleeves, trousers' legs or the like articles.

In this machine, the needle is mounted at the extremity of an arm, which receives an alternating movement of sufficient length for the needle to enter and recede from the cloth after having formed and left a loose thread loop upon the lower face of the cloth, the machine being automatically held stationary by a clamping device when the needle enters the two thicknesses of cloth, after which the needle passes out from the cloth and returns to the end of its stroke, where it stops, whilst the machine is moved along by hand for a distance corresponding to the interval between two successive loose thread loops.

The annexed sheets of drawings represented by way of example, one form of constructing the thread-tacking machine according to the invention.

Figure 1 is an elevation of one side of this machine.

Figure 1^a is a partial corresponding view for another position of the parts.

Figure 2 is the corresponding view of the other side.

Figure 3 is a transverse vertical section on line 3—3 of Figures 1 and 2, the machine being viewed endwise from the rear, i. e.

seen from the left of Figure 1 and from the right of Figure 2.

Figure 4 shows the needle separately and partly in vertical section.

Figure 5 shows diagrammatically the stitches and thread-loops formed by the machine through two thicknesses of cloth or fabric.

This machine for running tacking-threads comprises a housing *a* upon the front part of which is fixed a lever *b*; upon the latter is hinged at *b*¹ a second lever *b*², a plate spring *b*³ being interposed between the two levers. The movable lever *b*² has an extension arm *b*⁴ which by means of toothed sectors *b*⁵ and *b*⁶ actuates a toothed sector *c* pivoted at *c*¹ to the housing *a*. The movable lever *b*² comprises at its rear extremity a boss *b*⁷ forming an abutment for the plate spring *b*³ and also forming a stop upon the fixed lever *b*.

The toothed sector *c* meshes (see Figures 2 and 3) with a toothed pinion *c*² which is fast to a ratchet wheel *c*³ and loosely mounted on the shaft *d* of a flywheel *d*¹ journaled in the housing *a*. Upon this shaft *d* is keyed a plate *c*⁴ carrying a pawl *c*⁵ held in engagement with the ratchet wheel *c*³ by means of a spring *c*⁶. When the two levers *b*, *b*² are brought together, scissors-fashion, the toothed sector *c* actuated by the arm *b*⁴ causes the shaft *d* to turn in the direction of arrow (Figure 2) by the intermediary of the pinion *c*², the ratchet wheel *c*³, the pawl *c*⁵ and the plate *c*⁴; this shaft *d* is not affected when the lever *b*² resumes its initial position under the action of the plate spring *b*³, so that the shaft of the flywheel *d*¹ thus receives an intermittent movement of rotation in the same direction by the operation of the levers *b*, *b*².

Upon the shaft *d* is keyed, upon the opposite side of the flywheel *d*¹, a plate *e* which is provided with a pawl *e*¹ kept in engagement by a spring *e*² with the notch *f*¹ in a plate *f* loosely mounted on the shaft *d*. This plate *f* is fitted with a stud *f*² engaging in the slot *g*¹ in an arm *g* pivoted at *g*² to the upper part of the housing.

At its lower extremity the arm *g* is provided with a needle *h* slightly inclined from

the horizontal; this needle is fed with thread by the spool or reel h^1 supported by the spindle h^2 , the thread passing through the thread-guides h^3 and h^4 on its way from the spool h^1 to the needle h .

The needle-carrying arm g receives a movement of oscillation around its axis g^2 by the crank-disc f driven by the plate e fast to the shaft d of the flywheel d^1 .

10 The machine rests upon the material by three toothed wheels i mounted upon a spindle i^1 journaled at the lower part of the housing a ; upon this spindle i^1 is likewise keyed a disc i^2 provided with notches

15 i^3 . These notches are intended to receive a pawl j subject to the action of a spring j^1 ; this pawl constitutes one arm of a lever pivoted at j^2 upon the housing a . Another arm of this lever, j^3 , is situated in the path

20 of a spur g^3 , extending laterally from the needle-carrying arm g . A third arm j^4 carries an eccentric ramp j^5 intended to come into action upon the tail of the pawl e^1 effecting the drive of the crank-disc f by

25 the plate e ; this arm j^4 ends in a claw j^6 adapted to come into the path of a pin f^3 arranged at the periphery of the disc f driving the needle-carrying arm.

In the operation of this machine, it is 30 caused to travel by being pushed forward over two superposed thicknesses of material, following a pattern or outline traced upon the top material, whilst the levers b b^2 are operated in such a manner as to trans-

35 mit, as above explained, a movement of intermittent rotation to the shaft d of the flywheel and a movement of oscillation to the arm g carrying the needle h . At the moment when the needle h enters the two

40 superposed thicknesses of material k l (Figure 5), the machine is automatically stopped, the pawl j being maintained by its spring j^1 in engagement with one of the notches i^3 of the disc i^2 and thus preventing

45 the rotation of the toothed wheels i , that is to say, preventing the machine from rolling upon the cloth (position represented in Figure 1). At the end of the stroke of the needle entering the cloth, the spur g^3 upon

50 the needle-carrying arm g comes against the arm j^3 of the three-armed lever j (position represented in Figure 1^a), causing this lever to oscillate around its pivotal axis j^2 ; the pawl j is thus released from the notch i^3

55 upon the disc i^2 . The machine can then roll forward upon the cloth, for a distance x (Figure 5) corresponding to the interval between two adjacent notches, until the pawl j comes again into engagement at the

60 next notch. During this movement of the machine, the three-armed lever is maintained in its position by the fact that the point of the pawl j is in engagement with the periphery of the disc i^2 between the

65 two notches; the arm j^4 of this lever has

brought the eccentric ramp j^5 into the path of the tail of the pawl e^1 , so that the plates e and f will be disconnected from one another at the moment when the pawl e^1 passes in front of the ramp j^5 . At the same 70 time the pin f^3 upon the crank-disc f will have struck against the spur j^6 on the arm j^4 . The plate f is therefore no longer driven by the shaft d of the flywheel. During this time the needle-carrying arm g will have 75 returned to its former position (see Figure 1), withdrawing the needle h from the material and returning it to the end of its rearward stroke, where it will remain stationary. As soon as the pawl j has come 80 again into engagement with the following notch upon the disc i^2 , that is to say, as soon as the machine is again stationary relatively to the material, due to the oscillating movement of the lever having the three arms j , j^3 , j^4 , under the action of spring j^1 , the spur j^6 is brought outside of the path of the pin f^3 , of the crank disc f , and the ramp j^5 is brought outside of the path of the pawl e^1 , 85 the pawl e^1 is again brought by its spring e^2 into engagement with the notch f^1 of the crank-disc f ; the latter again actuates the needle-carrying arm g and the needle h again leads the thread through the two 90 thicknesses of material k l and forms a fresh 95 thread loop m . When the machine has followed the whole of the pattern or contour figured on the material k , the two thicknesses of material k and l are slightly separated one from the other and the thread is cut 100 between the two cloths or layers of material; thus there are obtained for the two opposite faces of the material two symmetrical outlines or patterns formed one by the loops m and the other by the thread ends n (Figure 105 5).

In order that the needle h shall not drag the thread o when passing out from the material, the needle is formed on either side of the hole or thread-eye p (Figure 4) with grooves p^1 p^2 in alignment with each other in the upper face and in the lower face of the needle, in such a way as thus to reduce friction between the thread and the needle; the thread which has been introduced through the material is thus easily retained by friction exercised between the thread and the material, so that it forms a loop m (Figure 5) when the needle passes out from the material.

110 It is understood that the described and illustrated form of carrying out the invention, is given only by way of example, and that numerous modifications can be made 115 without departing from the principle of the invention; thus for instance, the arrangement for effecting the rotatory movement of the flywheel shaft of the machine can be modified; this hand-control might also be 120 replaced by a small electric motor mounted 125 130

on the machine and receiving current from flexible conductors leading from a supply source.

What I claim is:

5. 1. A portable machine for running tacking threads through two superimposed thicknesses of cloth or the like along a predetermined outline, comprising a housing, a needle carrier pivotally mounted thereon, 10 means for imparting to the said needle carrier an alternating movement of a stroke sufficient to allow of the needle entering and passing through both thicknesses of material and coming back out therefrom after 15 having formed and left behind, each time, a loose loop of thread upon the under face of the lower cloth, locking means for automatically stopping the machine during the period the needle enters the two thicknesses 20 of material, means for automatically stopping the movement of the needle when it reaches the end of its backward stroke, means for automatically releasing the locking means of the machine, and hand actuated means for advancing said machine along the predetermined outline to the extent of a distance corresponding with the spacing apart of two consecutive loops of thread, for the purpose described.
- 30 2. In a thread tacking machine as claimed in claim 1, the provision of a needle-carrier pivotally mounted on the housing of said machine, a shaft journalled in said housing, a fly wheel keyed on said shaft, means for 35 rotating said shaft, a crank disc loosely mounted upon the shaft of said fly-wheel and engaging by its crank-pin the said needle carrier, and a pawl mechanism adapted to connect said crank-disc to the shaft 40 of the fly-wheel and to actuate the needle-carrier.

3. In a thread tacking machine as claimed in claim 1, the provision of a needle-carrier pivotally mounted on the housing of said machine, a shaft journalled in said housing, a fly wheel keyed on said shaft, means for 45 rotating said shaft, a crank disc loosely mounted upon the shaft of said fly-wheel and engaging by its crank pin the said needle-carrier, and a pawl mechanism adapted to connect said crank disc to the shaft of the fly wheel and to actuate the needle-carrier, the arrangement of two pivoted levers, one of which is fast with the housing 50 of the machine and the other of which comprises a toothed sector, a corresponding toothed sector gearing therewith and with a pawl mechanism, adapted to impart an intermittent rotation to the fly wheel shaft 55 which actuates the needle-carrying arm.

4. In a thread tacking machine as claimed in claim 1, the provision of toothed wheels adapted to rest upon the material, and journaled at the lower part of the housing, a 60 disc with notches fast with said wheels, and

a spring controlled locking pawl pivotally mounted on the housing and adapted to enter said notches, for the purpose described.

5. In a thread tacking machine as claimed in claim 1, the provision of toothed wheels 70 adapted to rest upon the material, and journaled at the lower part of the housing, a disc with notches fast with said wheels, and a spring controlled locking pawl pivotally mounted on the housing and adapted to 75 enter said notches, for the purpose described, the provision, on the needle-carrier, of a member adapted to unlatch the locking pawl from the notches of the disc fast with the carrier wheels of the machine, at the end 80 of the inward stroke of the needle, for the purpose described.

6. In a thread tacking machine as claimed in claim 1, the provision of toothed wheels 85 adapted to rest upon the material, and journaled at the lower part of the housing, a disc with notches fast with said wheels, and a spring controlled locking pawl pivotally mounted on the housing and adapted to enter said notches, for the purpose described, 90 comprising, a housing, a needle-carrier, pivotally mounted on the housing, a shaft journalled in the housing, a fly wheel keyed on the shaft, means for rotating the shaft, a crank disc loosely mounted on the shaft 95 and engaging by means of a pin, the needle-carrier, a pawl mechanism for connecting the crank disc to the shaft and for actuating the needle-carrier, and a lever pivoted on the housing machine, in combination with 100 a locking pawl on the pivoted lever, the lever comprising an arm for disconnecting the crank disc from the shaft of the fly wheel at the end of the backward stroke of the needle-carrier.

7. In a thread tacking machine as claimed in claim 1, the provision of toothed wheels adapted to rest upon the material, and journaled at the lower part of the housing, a disc with notches fast with said wheels, and a spring controlled locking pawl pivotally mounted on the housing and adapted to enter said notches, for the purpose described, comprising a housing, a needle-carrier, pivotally mounted on the housing, a shaft journalled in the housing, a fly wheel keyed on the shaft, means for rotating the shaft, a crank disc loosely mounted on the shaft and engaging by means of a pin, the needle-carrier, a pawl mechanism for connecting the crank disc to the shaft and for actuating the needle-carrier, and a lever pivoted on the housing machine, in combination with a locking pawl on the pivoted lever, the lever comprising an arm for disconnecting the crank disc from the shaft of the fly wheel at the end of the backward stroke of the needle-carrier, the provision, 110 on the disconnecting arm, of a finger adapted to cooperate with a pin upon the crank 115 120 125 130

disc to stop the rotation thereof and of the needle-carrier after disconnection of the said crank disc from the fly wheel shaft.

8. In a thread tacking machine as claimed in claim 1, a needle arranged upon a needle carrier in a position inclined to the horizontal, and in a direction opposite to that of movement of the machine upon the cloth to be operated on and grooves provided in alignment the one with the other, in the

upper and lower faces of the needle, and on either side of the thread hole, for the purpose described.

In testimony whereof I have signed my name to this specification.

GASTON VENDITTI.
